UNITED STATES PATENT OFFICE.

ALVIN DAVIS PUFFER, OF MEDFORD, MASSACHUSETTS.

FITTING FOR SODA-WATER APPARATUS.

SPECIFICATION forming part of Letters Patent No. 323,383, dated July 28, 1885.

Application filed February 9, 1885. (No model.)

To all whom it may concern:

Be it known that I, ALVIN DAVIS PUFFER, a citizen of the United States, residing at Medford, in the county of Middlesex and State of Massachusetts, have invented certain new and useful Improvements in Fittings for Soda-Water Apparatus; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to draft-cocks for soda-water apparatus and means for attaching the same thereto; and it consists in the construction and arrangement of parts herein-after set forth and claimed.

In Figure 1, I have shown, at A, a vertical central section of a portion of the shell of a soda-water fountain to which a discharge-cock, B, is attached, and in the general combination of parts as an entirety is embodied the subject of my invention. The outside or steel shell of said fountain, as shown at a, is provided with the usual lining, b, of tin, to maintain the purity of the contents. To obtain a medium by which to secure the discharge cock B to the fountain A, I have constructed a tubular bung, C, both interiorly and exteriorly screw-threaded, at c and d, respectively. Upon the outside one, d, is fitted the clamp-nut D, by means of which said bung is firmly attached to the fountain and forms an integral part thereof, while the interior one, c, receives and contains the shank E, exteriorly screw-threaded, of the cock B.

Upon the lower extremity or portion of the bung C, which lies within the fountain, I have cast or formed an external shoulder, f, which rests under the shell a of the fountain, while a similar oppositely-disposed but corresponding shoulder or annular lip, g, is shown as projecting within the bore of the bung C. This annular lip g forms a seat, upon which I dispose the packing F, while from the disposition of the parts it is evident that the lower extremity of the shank E of the cock B, when the latter is in proper position, will compress said packing, and thus secure a tight joint to prevent access of the fluid contents of the

fountain from entering the screw-threads, as usually occurs under the present system of securing the cock to the bung of the fountain 55 or other vessel.

The discharge-pipe leading from the fountain is shown at G, secured to the cock B by solder, (shown in black,) and unites with the main discharge-outlet H, which is formed in 60 tin or other suitable metal.

From the above description it will be readily understood that the action of securing the discharge-faucet B when in place compresses the packing F and the screw-threaded surfaces 65 upon the cock, and its retaining bung C cannot be reached by the fluid contents—such as soda or mineral water—contained within the vessel. Thus, in case the tin or silver coating wears from off the screw-threads and exposes 70 the brass composing them, this metal cannot produce any deleterious effect upon the beverage, and the purity of the latter is effectually preserved. Furthermore, the destruction 75 of the metal forming the fittings is obviated, and the several parts may be taken apart more readily, will last longer, and at the same time a tight fit can always be secured without substituting new parts.

In Fig. 1 I have shown the parts as adapted 80 and arranged in connection with a steel soda-water fountain or other analogous vessel, while in Fig. 2 is a slightly-modified form, as adapted to be employed with copper fountains; but in both cases the result and object of my invention is accomplished in substantially the same manner, and consists in preventing any access 85 whatsoever of the contents of a fountain or vessel under pressure to the peripheral screw-threaded surface which exists between the 90 bung and the discharge-cock.

It is very evident that various modifications may be introduced by persons skilled in the art in the method of constructing and forming the interior annular lip or packing-seat, g'. 95 Thus by means of one of these, which is shown in Fig. 3, I am enabled to adapt the old form of bung C', so that it will accomplish the object and purpose of my invention. In said Fig. 3 the ordinary bung is interiorly screw-threaded its entire distance, and I have therefore formed the interior lip separate and distinct from the bung, casting an annular piece, g', exteriorly screw-threaded, and of a diam-

ter adapted to be screwed in the bung and secured permanently in place by solder or otherwise; but I consider this involves the spirit of my invention, since I consider the latter to consist substantially in the adaptation and arrangement of the fittings to prevent access of the fluid contents of the vessel under pressure to the screw-threaded surfaces of the cock and its inclosing-bung.

10 I claim—
The combination of shell A and discharge-

cock B with retaining-bung C, having lip *g*, the draft-pipe G, and the packing F, said cock compressing said packing to form a tight joint, substantially as set forth.

15 In testimony whereof I affix my signature in presence of two witnesses.

ALVIN DAVIS PUFFER.
